10 Claims. (Cl. 179—27)

The present invention relates to telephone systems and automatic switches suitable for use therein and is more particularly concerned with arrangements for the selection of trunk lines in automatic trunk exchanges. The invention is moreover particularly concerned with group selector switches of the so-called two-digit type, that is, requiring the transmission of two digits to complete their operation and preferably these switches operate on the longitudinal and rotary principle.

In exchanges of the kind contemplated where automatic switches are used for selecting trunk lines, the operator usually keys up the routing digits required into a keysending equipment which thereupon sets up the automatic switches. In a known arrangement of this type the switches which have direct access to the trunk lines are of the two-digit vertical and rotary type so that in an exchange employing first, second and third selectors, the third digit keyed by an operator will cause a third selector to step vertically to select a level on which is situated the required group of trunks. In response to the keying of as a fourth digit the switch wipers are advanced into engagement with the first set of outlets in the level selected. The first outlets of each level are not connected to a trunk but are wired back into the switch so that if the switch wipers are set thereon by a single impulse a relay in the switch is operated to initiate the rotary hunting operation over the group of nine trunks connected to the remaining nine outlets of the level. One object of the invention is to provide a means whereby these first outlets may be utilised for connection to trunks, thereby extending the capacity of trunk groups from nine to ten trunks.

In the prior arrangement if all outlets in the trunk group are engaged, the wipers are rotated to the 11th position and the call is placed in storage. When a trunk in the required group becomes free the operator is signalled from the call storing equipment and she may then cause the third selector to restore to the rotary normal position and then re-search the level. Another object of the invention is to provide the switch with further facilities whereby it may also perform a hunting operation over a sub-group of high grade trunks in a main group of trunks and whereby if all outlets in either the main group or the sub-group are tested and found to be engaged the operator may cause the switch to restore from the end of either of these groups and re-search the whole main group.

According to one feature of the invention a telephone system including a group selector switch is arranged so that initiation of the hunting movement after the group selecting movement has taken place is dependent on the receipt by the switch of a signal different from those effecting the movement of the switch which signal results from a specific operation at the calling point.

According to another feature of the invention in a group selector switch for use in telephone or like systems after unsuccessful hunting for an idle line in a group has taken place the switch is adapted to hunt over a different group in response to a control signal from the calling point.

According to another feature of the invention in a group selector switch for use in telephone or like systems after unsuccessful hunting for an idle line in a group has taken place the switch is adapted to hunt again over a larger group of lines including the lines of the original group.

According to a further feature of the invention in a group selector switch for use in telephone or like systems after unsuccessful hunting for an idle line in a group has taken place a busy signal is transmitted back in a circuit independent of the switch wipers which signal is adapted to be removed by an operation at the calling point without the position of the switch wipers being changed.

The invention will be better understood from the following description of one method of carrying it into effect, reference being had to the accompanying drawings comprising Figs. 1 and 2 which when arranged side by side form a circuit diagram of a 100-outlet two-digit group selector which is suitable for use in an automatic trunk exchange.

The switch is of the two-directional type and has so-called rectangular movement in that no release magnet is provided, the restoration of the switch to normal being effected by stepping the wipers forward to the end of the level and then allowing them to complete their restoration by a vertical and rotary movement.

For the purpose of the description the selector is assumed to be used as a third trunk selector and has access to ten groups of ten trunk lines each, one such group being accommodated on each level. It will further be assumed that the originating operator at an automatic trunk board desires access to a trunk group on level 3 of the switch, this main group including a sub-group of

five high grade trunks which are located on outlets 6 to 0 of the level.

When the switch is seized from the preceding second trunk selector, the loop extended forward 5 over the negative and positive conductors from an impulse sender which is temporarily associated with the operator's keyset during the setting up of the connection operates relay A and battery potential extended from the operator's 10 position circuit over the S lead operates relay CS by way of its upper winding. Relay CS thereupon at armature c_1 connects earth from the off-normal contacts N3 to operate relay B which on operating, at armature b_1 locks independently 15 of the contacts N3 and at armature b_2 applies a guard earth to the incoming P conductor. Relay C is also operated over its right-hand winding by way of armature b_6 and resistance YC and at armature c_1 it prepares an impulsive circuit 20 to the vertical magnet VM by way of armature a_1 and the left-hand low resistance winding of relay C. Although relay DF is in series with the operating windings of relay A it is non-operative under the above condition by reason of the differential arrangement of its windings and for this 25 reason also it has no effect on the response of relay A to subsequent trains of impulses.

When the first train of three impulses is received in response to the keying up by the operator of the third digit 3 in the number, relay A 30 responds and on each release of this relay earth is extended over armatures b_1 , c_1 , c_1 , ar_4 and a_1 , left-hand low resistance winding of relay C, armature e_5 , contacts NR3, magnet VM to battery 35 and accordingly the switch wipers are raised to the desired level 3. On the first vertical step the off-normal springs are mechanically operated and at contacts N3 earth is extended over armature h_3 , contacts NR2 and armatures e_2 and b_6 40 to short-circuit the right-hand energising winding of relay C so that this relay will remain held during the impulse train on its left-hand winding but will release a short interval after completion of the train.

Assuming now that the operator wishes to gain access to any one of the group of ten outgoing 45 trunk lines on this level, she will have keyed up 1 as a fourth digit. In response to the keying of this particular digit the sender transmits a special signal immediately after the end of the 50 third digit for instance as described in British Specification No. 10,546/37. This signal momentarily unbalances the incoming loop to relays DF and A for example by the connection of earth 55 potential thereto so that the differential relay DF now operates while relay A remains held on its upper winding. Relay DF at armature df_1 operates relay TA over its middle winding and this relay thereupon locks temporarily over its 60 left-hand winding in series with armature ta_1 , off-normal contacts N2, rotary magnet interrupter contacts rm and armature ta_3 to earth. At armature ta_1 the short-circuit is now removed from the left-hand winding of relay AR which 65 operates in series with the middle winding of relay TA while at armature ta_2 the right-hand winding of relay TA is connected to the test wiper P in preparation for testing for a free outlet. Relay AR upon operating, at armature ar_5 locks 70 over its right-hand winding in series with resistance YB, at armature ar_3 provides an additional short-circuit to the right-hand energising winding of relay C and at armature ar_4 disconnects the impulsive circuit extending to the rotary magnet RM. On the release of relay C, a

self-interrupted driving circuit is completed for the rotary magnet RM from earth, armature ta_3 , interrupter contacts rm , contacts N2, armatures c_4 , r_1 and h_1 , magnet RM to battery. On the first energisation of the magnet RM, the wipers 5 are advanced into engagement with the first set of contacts in the level selected whereupon the rotary off-normal springs NR are mechanically operated and also the magnet interrupter contacts rm are opened. 10

If the test wiper P encounters an engaged outlet, that is, one marked by the presence of earth potential, relay TA will be maintained operated on its right-hand winding and the disconnection of the holding circuit over its left-hand winding by the contacts rm is therefore without effect. However the rotary magnet RM releases and when the interrupter contacts again close the magnet is again energised to advance the wipers 15 to the next set of contacts. This stepping operation continues automatically until either a free trunk line in the selected group is found or alternatively the wipers are rotated to the 11th position where the call is placed in storage. 20

Assuming first that a free outlet is encountered, there will be no earth potential extended over the P wiper to hold relay TA operated when the interrupter contacts rm open and this relay therefore quickly restores and at armature ta_3 25 opens the magnet driving circuit and at armature ta_2 immediately guards the outlet seized by extending earth over armatures b_5 , ar_1 and ta_2 to the P wiper. A circuit is now completed from earth, armature b_5 , windings of relays HX and H in series, armatures sr_2 , ta_5 and ar_2 , magnet 30 RM to battery in order to operate both of these relays, the magnet RM being non-operative in this condition, whilst at armature ta_6 relay C is re-operated due to the removal of the short-circuit from its right-hand winding. Relay HX 35 at its armatures hx_1 to hx_6 switches the incoming leads through to the seized outlet comprising a trunk relay set, one of which is provided for each trunk line, and also at armature hx_6 it disconnects relay CS which releases and opens 40 the holding circuit of relay B. On the operation of relay C the incoming P lead is also extended through over armatures c_2 and h_4 and during the release time of relay B a guard and hold earth is maintained on the P conductor until an 45 earth is returned from the trunk relay set. Relay B on releasing releases relay AR.

In case all the outlets in the level selected prove busy, the wipers are rotated to the 11th position where the cam springs S are mechanically operated and since in this position the P contacts are left unwired, relay TA releases quickly and cuts the drive. Cam contacts SI remove the short-circuit from relay C so that it re-operates and at the same time they complete an 50 operating circuit for relay SR which thereupon at armature sr_2 disconnects the operating circuit for relays H and HX, this circuit being normally completed on release of relay TA, so that these two relays fail to operate and consequently 55 relays CS, B and AR remain operated.

It will be understood that the multiplied 11th contacts on all levels of the banks PS and S extend over pairs of common leads such as 12 and 13 to call storing equipments, one of which is 60 provided for each group of trunks. Each call storing equipment serves to display the number of calls awaiting idle trunks in the associated group and gives facilities for automatically putting the trunk group into delay when any prede- 65 70 75

terminated number of calls are waiting. When a trunk line in a group becomes free, the associated call storing equipment signals all operators waiting for that line and they, in a manner to be described, cause the release of the trunk selector to which they are connected, and it then searches for the free trunk. Call storing equipment of this type is disclosed in Patent No. 2,093,249.

Returning again to the circuit operation, relay SR at armature *sr3* extends battery potential via resistance YD over the PS wiper and bank in order that the call may be registered in the call storing equipment and at armature *sr4* connects relay TF to the S wiper in preparation for the reception of a trunk free signal. The release of relay TA also completes a circuit for relay G from earth, armature *b1*, contacts *N3*, armature *h3*, contacts *NR2*, armatures *ta4*, *hs3* and *e4*, upper winding of relay G to battery. Accordingly at armature *g3* a busy tone transformer is connected up over common lead 10 to the lower winding of relay A whereupon busy tone is applied by induction through the upper two windings of this relay to the incoming speaking conductors in a balanced circuit and thence is transmitted to the operator.

The operator on receiving busy tone may remove it by operating the non-locking "ring call" key of the connecting circuit involved the effect of which is to unbalance the incoming loop so that relay DF is again operated. Relay DF at armature *d1* re-operates relay TA from earth, armature *b1*, contacts *N3*, armatures *sr1*, *d1* and *ta1*, middle winding of relay TA to battery and this relay thereupon locks over its left-hand winding by way of armatures *ta1* and *ta3*. At armature *ta4* relay G is now released and at armature *g3* it opens the busy tone circuit to the operator. The connection is retained in order to await a trunk free signal from the associated call storing equipment but in the meantime the operator may attend to other calls.

As soon as a trunk in the required group becomes free, interrupted earth potential is fed back over common lead 13 and the S wiper to effect the intermittent operation of relay TF and similar relays in any other third trunk selectors which are awaiting an idle trunk in the group. Each time relay TF operates the low resistance earth normally applied to the incoming S lead over the upper low resistance winding of relay CS is replaced at armature *t1* by a high resistance earth comprising the two windings of relay CS in series and this brings about the release of a relay connected to the S lead in the operator's connecting circuit which in turn flashes the supervisory lamp in place of the normal steady glow.

The operator may now cause the trunk selector to release to its rotary normal position and research the level, by operating her "unlock-call" key which is of the non-locking type. On the operation of this key positive battery is applied to the S lead so that rectifier MRB now becomes conducting and enables relay RL to operate over its left-hand winding. Relay RL at armature *r1* releases relay SR which at armature *sr2* again prepares an operating circuit for relays H and HX and at armatures *sr3* and *sr4* removes resistance YD and relay TF from the wipers PS and S respectively. Armature *r1* also short-circuits relay C which releases in order to prepare an energising circuit for the vertical magnet VM, while at armature *r2* the right-hand winding of relay TA is disconnected from the P wiper and at ar-

mature *r3* relay TA is maintained over its middle winding in series with the left-hand winding of relay AR. At armature *r4* an energising circuit is completed for the vertical magnet VM is follows: earth, armature *ta3*, contacts *rm* and *N2*, armatures *c4* and *r4*, low resistance right-hand winding of relay RL, rotary off-normal contacts *NR3*, magnet VM to battery.

The vertical magnet pawl when operated is arranged to engage with an extension arm of the rotary detent and move it out of engagement with the rotary ratchet member so as to initiate the rotary release of the wipers along the path over which they have been set, for instance in the manner described in Patent No. 2,028,689.

When the wipers reach their rotary normal position, the vertical ratchet member re-engages with the vertical holding detent thus preventing further release of the wipers to their fully restored position. In this position the rotary off-normal springs are restored while at the commencement of the release operation the 11th step cam springs are also restored and at contacts *S1* maintain a short-circuiting earth on relay C in preparation for re-search of the level. The restoration of contacts *NR3* releases the vertical magnet VM and opens the holding circuit of relay RL. This relay upon releasing reconnects the winding of relay TA to the P wiper at armature *r2*, disconnects the middle winding of relay TA at armature *r3* and at armature *r4* completes a self-interrupted driving circuit for the rotary magnet RM so that re-search of the group now takes place in the same manner as the initial search.

At the end of the conversation the operator throws her "release" key on reception of the clearing signals on her call and answering supervisory lamps and in response to this operation the trunk relay set removes the hold earth from the P lead thus bringing about the release of relays H and HX. Relay H thereupon at armature *h2* opens the circuit of relay C and when this releases a self-interrupted driving circuit is completed for the rotary magnet RM as follows:— 40 earthed delayed alarm equipment, common lead 11, test jack springs T, armatures *b3*, *c1* and *ta3*, contacts *rm* and *N2*, armatures *c4*, *r4* and *h1*, magnet RM to battery. The wipers are accordingly advanced to the 12th position whereupon 50 they restore vertically under gravity and then rotate under spring control under the banks to their full normal position where the off-normal contacts *N2* open the magnet energising circuit.

A momentary unguard interval comprising the sum of the release times of relays H and C is provided on the incoming P lead to allow preceding switches to release with a minimum of delay. On release of relay C the guard earth is replaced over contacts *N1* and armature *c2* until 60 contacts *N1* open when the switch reaches normal.

Considering now the case in which the operator requires access only to the sub-group of high grade trunks in the main group of trunks on the level, she keys 6 as a fourth digit in order that the wipers will be advanced to the first outlet of the sub-group, from which position automatic rotary hunting over the sub-group may take place.

The circuit operation proceeds as previously described to the end of the vertical train of pulses when after a slight interval relay C releases since relay A remains steadily operated. Earth is then extended from armature *b1*, contacts *N3*, armatures *h3*, *ar3*, *hs4* and *c3*, lower winding of relay 70, 75,

CR, contacts NR3, magnet VM to battery whereupon relay CR operates but the magnet VM does not. At armature *cr1* a circuit is now completed for relay E and on operation of this relay it locks up independently of armature *cr1* at armature *e1*, at armature *e5* prepares an impulsing circuit for the rotary magnet RM and at armature *e2* removes the short-circuiting earth from the right-hand winding of relay C which then re-operates. Relay CR now remains held over its upper winding by way of armatures *cr2*, *a1*, *ar4*, *cl*, *cs1* and *b1* since its lower winding is disconnected at armature *c3*.

In response to the keying of the fourth digit a train of six impulses is transmitted from the sender and relay A again responds. On each release of relay A earth is extended via the left-hand winding of relay C and armatures *e5* and *h1* to energise the rotary magnet RM so that the wipers are rotated to the desired position. Due to its slug relay CR remains operated over its upper winding during the train of pulses, while relay C also holds up since its right-hand winding is short-circuited on the first rotary step at contacts NR2 and armature *e2*.

At the end of the train of pulses relay C restores after a short interval and at armature *c1* opens the holding circuit of relay CR which commences to release slowly. At armatures *c5* and *cr3* relay HS is now connected to the *P1* wiper during the release time of relay CR and since the wipers have been positioned to the first outlet of the sub-group, relay HS will operate on its upper winding in series with a resistance battery potential connected to the first outlet of the group on the *P1* bank. Relay HS locks over its lower winding by way of armatures *g1*, *hs4*, *ar3* and *h3* and at armature *hs5* prepares a further energising circuit for the rotary magnet RM.

Since relay E is now operated the release of armature *c6* connects an earth to relay TD. If the first trunk in the sub-group is found to be free, relay TD operates in series with resistance *YB* since there will be no busying earth extended back over the *P* wiper and metal rectifier MRA in a conductive direction to prevent its operation. Relay TD thereupon at armature *td2* operates relays H and HX which switch the lines through in the normal manner while at armature *td1* a guard earth is extended from armature *b5* on to the outlet seized. Relays H and HX on operating re-operate relay C by removing the short-circuit at armature *h3* and release relays A, CS and B in the normal manner and at armature *c6* relay TD is released and the *P* lead is extended through over armatures *c2* and *h4*. On the release of relay CR after its slow release period, relay HS releases since its lower winding is disconnected at armature *h3* and relay E also releases. The circuit conditions during conversation are now as before described.

If the first trunk in the sub-group is engaged, an earth is extended over the *P* wiper and rectifier MRA to shunt relay TD and prevent its operation. On the release of relay CR the energising circuit for relay E is disconnected since relay HS is now operated and on the release of relay E the short-circuit is removed from relay C at armature *e2*. Relay C now re-operates and at armature *c6* it extends earth over armatures *g2*, *hs5* and *h1* to energise the rotary magnet RM whereupon the switch wipers are advanced to the next outlet. Earth is now extended over armatures *c1* and *ta3*, operated rotary magnet

interrupter contacts *rm* and armatures *hs2*, *hs3* and *e4* to operate relay G on its upper winding. At armature *g1* earth is extended by way of the lower winding of relay G to the winding of relay TD while the lower winding of relay HS is disconnected but this relay remains held operated for a further short interval due to its slug. Moreover at armature *g2* the rotary magnet circuit is opened and the magnet restores and opens the energising circuit of relay G over its upper winding at contacts *rm*. If this second outlet in the sub-group is also busy, relay G now releases since the earth extended over the *P* wiper prevents it holding on its lower winding in series with the winding of relay TD. On the release of relay G a circuit is again completed for relay HS at armature *g1* by way of its lower winding, this relay having been held operated during this time due to its slug, while at armature *g2* the magnet RM is again energised. Interaction between relay G and the magnet RM continues until a free outlet in the sub-group is reached, or alternatively the wipers are rotated to the last outlet in the sub-group.

When a free outlet is reached, relay G holds in series with relay TD which operates and energises relays H and HX as before. On operation of relay H relays G and TD are released at armature *h3*, and relay HS also releases after its slow period.

If all outlets in the sub-group prove to be busy, when the wipers reach the last of these outlets relay G holds operated over its upper winding, armatures *e4* and *hs3*, high resistance *YE*, armature *c5*, *P1* wiper and bank to an earth which marks the last line of the sub-group. On the release of relay HS after its slow period, relay G remains held over its upper winding, armatures *e4*, *hs3* and *ta4*, contacts NR2, armature *h3*, contacts N3, armature *b1* to earth and accordingly busy tone is returned to the operator over armatures *g3* and *hs1*.

The operator on finding that all high grade trunks in the sub-group are busy may decide that an ordinary trunk in the group may be utilised to complete the connection and she therefore again operates her "unlock" key to bring about the operation of relay RL. The switch now restores to the rotary normal position and then re-searches the whole group of trunks on the level in the manner previously described.

Facilities are also provided whereby the operator may select any particular trunk of a group except the first of a main group or the first of a sub-group therein, and if this trunk is found to be busy, no hunting takes place but the switch camps on the trunk until it becomes free. Generally the above facility is likely to be required whenever an operator is setting up an exceptionally long distance call when it is important to utilise the highest grade trunk line available.

Considering now the circuit operation, on the completion of the train of rotary setting pulses, relay C restores and opens the holding circuit of relay CR in the normal manner. Relay HS is connected as before to the *P1* wiper but since the wipers have not been positioned to the first line of the sub-group, relay HS cannot operate. Earth is also connected at armature *c6* to relay TD which operates in series with resistance *YB* if the selected trunk is free and the operation proceeds in a normal manner. If the selected trunk is busy however, the earth potential encountered by the *P* wiper will prevent relay TD

from operating. Relay CR releases after a short interval but relay E now remains held over armatures e_1 , h_5 , a_3 and h_3 , contacts N3 and armature b_1 to earth. An earth is therefore maintained on the left-hand terminal of relay TD over contacts NRI and armature c_6 and e_3 and the switch wipers will remain on the selected outlet until it becomes free, when relay TD operates and operates relay H and HX to switch the connection through. When this occurs the operator is signalled in the normal manner by the darkening of her supervisory lamp due to the change-over from a low resistance earth normally extended on to the S lead by way of the upper 10 low resistance winding of relay CS to a high resistance earth connected to the S lead by way of a high resistance relay in the trunk relay set associated with the selected trunk.

Leads NA and NB and resistance YA are utilised in connection with the inclusion of thermionic repeaters, resistance YA serving as a line balancing arrangement during the setting of the switch.

Rectifier MRA is provided to prevent an earth 25 by way of the winding of relay TD from being extended on to the P wiper during the camp-on period, which would influence other switches connected to the same outlet.

We claim:

30 1. In a telephone system, a selector switch having access to groups of lines and controlled over a calling subscriber's line by signals of one character to operate the switch to elect a group of lines, means in the switch operated before the 35 switch is released responsive to a signal over the calling subscriber's line different from that used to directly operate the switch for initiating a hunting movement of the switch to select an idle line in the selected group.

40 2. A selector switch having access to groups of lines and controlled over an incoming line to elect a group of outgoing lines and operated thereafter to hunt for an idle line in the elected group, and means in the switch operated in response to a control signal over the incoming line before the switch is released to cause the switch to hunt over a different group of outgoing lines after an unsuccessful hunt over the selected 45 group.

50 3. A selector switch as claimed in claim 2 in

which the second group over which the switch hunts also includes the first group.

4. A selector switch as claimed in claim 1 in which the signal for initiating the hunting operation consists of an unbalanced condition of the 5 circuit extending from the calling line to the switch.

5. A selector switch as claimed in claim 2 in which there is a differential relay in the switch operated by the control signal to cause the switch 10 to hunt over said different groups.

6. A selector switch as claimed in claim 1 in which there is a differential relay in the switch operated by said control signal to initiate said hunting operation. 15

7. A selector switch having access to groups of lines and controlled over a calling subscriber's line to elect a group of lines and then hunt for an idle line in the elected group, means in the switch operated in response to a special control 20 signal from the calling line to initiate said hunting operation, means for returning a busy signal to the calling subscriber in case all the lines are busy, and means in the switch operated in response to said special control signal after an 25 unsuccessful hunting operation to remove the busy signal without releasing the switch to normal.

8. In a telephone system, a selector switch having access to groups of lines, means for operating the switch to elect a group of lines and to then select an idle line in the elected group, and means in the switch controlled solely over the calling subscriber's line for causing it to hunt over a different group than that first tested after 30 an unsuccessful hunt for an idle line in the elected group and while the switch is maintained partially operated. 35

9. A selector switch as claimed in claim 8 in which there is means for directing the switch to the first line of a selected portion of the first group to thereby cause hunting only over that portion in the first instance. 40

10. A selector switch as claimed in claim 8 in which there is means for directing the switch to a line in the group other than the first to prevent hunting operations and give a busy signal in case that particular line is busy. 45
